UNITED STATES PATENT OFFICE.

WALTER P. MURPHY, OF CHICAGO, ILLINOIS.

CAR-ROOF.

1,030,600.

Specification of Letters Patent. Patented June 25, 1912.

Application filed August 10, 1910. Serial No. 576,546.

To all whom it may concern:

Be it known that I, WALTER P. MURPHY, a citizen of the United States, residing at Chicago, in the county of Cook and State of Illinois, have invented certain new and useful Improvements in Car-Roofs, of which the following is a specification.

In certain car roofs comprising metallic sheets, it has formerly been the practice to fasten the edges of the sheets at the eaves by means of nails and by clips secured to the molding, said clips extending up and over the edge of the sheets. These nails and clips resist the tendency of the sheets to slide longitudinally at the same time that they hold the sheets down on the substructure. This tendency of the sheets to slide longitudinally causes a strain upon the nails, clips or other fastening means in the direction in which their resistance is least, as the clips tend to turn outwardly about their lower ends as fulcra.

One of the objects of my invention is to eliminate the use of nails and of clips secured to the molding or side of the car to hold the outer edge of the sheet down, except at the seams between the sheets.

Another object of my invention is to prevent puckering of the roof sheets.

Still another object of my invention is to permit the end portion of the sheet to work up and down over a fascia having an upper rounded corner; and with these and minor objects in view, my invention consists of the parts and combination of parts as will be hereinafter pointed out.

In the drawing, Figure 1 is a side elevation of a car, parts being broken away, with my invention embodied; Fig. 2 is a section on the line 2—2, Fig. 1; Fig. 3 is a detail sectional view of a car at the eaves showing a modified form of roof clip; Fig. 4 is a perspective view of the clip shown in Fig. 3; Fig. 5 is a detail sectional view of a roofing sheet having the clip secured on its under face; Fig. 6 is a detail sectional view of a roofing sheet bent upon itself and riveted; and Fig. 7 is a side elevation of the roof seam clip.

1 represents a car of any approved design; 2 the roofing sheets which are joined at their side edges by means of any of the well known approved seams, which permit a relative movement of the sheets.

Heretofore, it has been a common practice to bend the outer edges of the roofing

sheets down over the eaves of the car and secure the bent over portion to a fascia or to the side of the car by means of nails, clips, etc., but it has been found that this results in the tearing of the sheets at the eaves, where they are bent over, inasmuch as the tendency of the sheets to slide longitudinally is resisted, thus permitting water, snow, dust and cinders to work up under the roofing sheets thence into the car. I overcome these objections and the faulty construction by riveting or otherwise suitably securing to the roofing sheet 2 clips 8, conforming to the bend of the sheet at the eaves as shown in Fig. 1. One arm of the clip is secured to the main body or portion of the sheet, while the other arm is secured to the turned down portion 9 of the sheet.

10 is a roof seam clip provided with a hood 11 constructed to close the open end of the seam 12 and cover a portion of the seam as shown in Fig. 1. The apron of the seam clip is wide enough to bridge the gap between the turned down portion of the sheets at the seam and is provided with wide spreading side wings 13, which project over the down turned portion 9 of the roof sheets, as shown, thereby assisting the clips 8 in holding the roof sheets in their bent position.

The wings or arms 13 are slightly thinner than the apron of the seam clip as shown in Fig. 7, in order that the under face of the apron may be secured snugly against the fascia or side of the car, the extra thickness of the apron serving as a spacing block for the wings 13, thus spacing them from the fascia or side of the car to permit of the portion 9 of the roofing sheets occupying a position between them and the side of the car or fascia.

The clip is provided with an upper and lower opening. A bolt, nail or lag screw 13^a is inserted in the upper opening, the body thereof passing between the side edges of adjacent sheets and above the down-turned ends of the sheets which overhang the eaves of the car, whereby the clip is secured to the car at the eaves between the down-turned ends of the sheet. The bolt, nail or screw 13^b is passed through the lower portion of the clip below the down-turned ends of the roof sheets. This arrangement provides a secure fastening for the clips as the upper bolt 13^a resists the tendency of the clips to tilt outward when the roof sheets move endwise. This roof clip may

be secured to the under face of the roofing sheets as shown in Fig. 5; and it may be provided with a reinforcing rib 14 as shown in Figs. 3 and 4. The roofing sheets may 5 be doubled back at the outer end and have the doubled portion turned down over the eaves, which portion, after being bent, is riveted together as shown in Fig. 6. This latter construction serves as a double flashing. By riveting the doubled back portion 10 after it is bent down to form the bend at the eaves, I firmly lock the metal in this downward bend.

By this construction, I eliminate the danger of the down turned portion of the roof sheets puckering, curling up or outwardly, and further eliminate the liability of the roof sheets tearing, as happens in the constructions where the end of the sheet is 15 nailed or otherwise rigidly secured to the fascia or side of the car. Another advantage of this construction is that the end portion of the sheet is free to work up and down over the rounded corner of the fascia. 20 The wings 13 of the roof seam clip hold the downwardly bent portion 9 from bending outwardly or curling at the side edges of the sheet.

The fascia 15 extends outwardly far 25 enough beyond the clips and roof sheets to protect them against "side scraping" and is of such shape that water will readily run off of it free from the side of the car.

What I claim is:—

30 1. A car roof comprising metal sheets 35 flexibly connected by interlocking flanges extending from the eaves to the ridge, the outer portion of each sheet being bent down over the eaves, and means secured to each 40 sheet in the outer bent down portion to maintain the angular relation of the bent portion relative to the main body portion 45 of the sheet.

2. A car roof comprising metal sheets 45 flexibly connected by interlocking flanges extending from the eaves to the ridge, the outer portion of each sheet being rounded and bent down over the eaves, a fascia having a rounded upper corner, braces secured

50 in the rounded and bent down portion of the sheets to maintain the shape of this portion as said portion works up and down over the rounded corner of the fascia.

3. The combination with a car roof sheet, 55 the outer portion of which is bent down to form an eaves bend at right angles to the main portion of the sheet, of brackets secured in said bend to stiffen the bent portion and maintain the angular relation between said bent portion and the main portion 60 of the sheet.

4. In a car roof comprising roof sheets 65 movably secured thereon having down-turned ends overhanging the eaves, eaves 70 clips arranged at the joint between adjacent roof sheets to overlie the same, said eaves clips comprising base portions and wing portions extending from the outer edges of the base portions and overlapping the down-turned ends of adjacent roof sheets, 75 said base portions being of greater thickness than the wing portions, whereby the wing portions are spaced from the roof sheets and loosely secure the latter at the eaves corners thereof. 75

5. In a car roof comprising roof sheets 80 movably secured thereon having down-turned ends overhanging the eaves, eaves 85 clips arranged at the joints between adjacent roof sheets to overlie the same, said eaves clips comprising base portions secured to the car at the eaves between the down-turned ends of the sheets, and wing portions 90 extending from the outer edges of said base portions and overlapping the down-turned ends of adjacent roof sheets, said base portions being of greater thickness than the wing portions, whereby the wing portions are spaced from the roof sheets and loosely secure the latter at the eaves corners thereof. 90

In testimony whereof I affix my signature in presence of two witnesses.

WALTER P. MURPHY.
